UNITED STATES PATENT OFFICE.

MILTON TIBBETTS, OF DETROIT, MICHIGAN, ASSIGNOR, BY MESNE ASSIGNMENTS, TO
PACKARD MOTOR CAR COMPANY, OF DETROIT, MICHIGAN, A CORPORATION OF
MICHIGAN.

WIND-SHIELD.

1,120,863.

Specification of Letters Patent. Patented Dec. 15, 1914.

Application filed June 6, 1903. Serial No. 437,176.

To all whom it may concern:

Be it known that I, MILTON TIBBETTS, a citizen of the United States, and resident of Detroit, in the county of Wayne and State 5 of Michigan, have invented certain new and useful Improvements in Wind-Shields, of which the following is a specification.

This invention relates to wind shields for motor vehicles, and has particular reference to such shields made up of an upper 10 and lower sash, which are adapted to fold together.

Its objects are to provide means for easily and conveniently bringing the upper sash 15 into a position against the lower sash without utilizing much room in the operation, so that there will be no interference by the numerous parts of the vehicle which would be in the way if the sashes were hinged 20 together to fold in the ordinary way.

To this end my invention embodies mechanism by which the upper sash may be lowered in a vertical plane parallel with the lower sash, and close against said lower 25 sash. Briefly stated, the sashes fold by a relative endwise motion of pure translation in a circular path.

Other features and details of my invention will be apparent from the following 30 description and claims.

In the accompanying drawings:—Figure 1 is a front view of a portion of a motor vehicle having one form of my wind shield applied thereto; Fig. 2 is a side view of 35 what is shown in Fig. 1; Fig. 3 is an enlarged edge view of a portion of the two sashes viewed from opposite sides, the sashes being in normal position and in line; Fig. 4 is a similar view showing the upper 40 sash pulled out to a position out of line with the lower sash and ready to be lowered; Fig. 5 is a similar view showing the upper sash in lowered position; Fig. 6 is a detail sectional view of the pivot joint for the arm carrying the upper sash; Fig. 7 is a cross 45 section on the line 7—7 of Fig. 6, showing my split sleeve arrangement for clamping the pivot joint; Fig. 8 is a sectional view showing the meeting edges of the two sashes 50 when in position, one above the other; Fig. 9 is a rear view of the two sashes with the upper sash partly lowered; Fig. 10 is a rear view of the two sashes in normal position, and showing a modified form of means for 55 lowering the upper sash; Fig. 11 is an edge view of what is shown in Fig. 10; Fig. 12 is a detail view of the modified pivot arms and cams for automatically moving the upper sash out of line with the lower sash; and Fig. 13 is a similar view showing the 60 position of the pivot arms and cams when the upper sash is in lowered position.

In these drawings, 1 represents the side bar of the vehicle frame, 2 represents the engine housing, and 3 represents the dash- 65 board of the vehicle.

My wind shield is mounted on the dash- 70 board 3 and is composed of a lower stationary sash 4, and the upper movable sash 5, which sashes in normal use are in line one 70 above the other. The lower sash is supported by the brace rods 6 connected with the frame.

In the form shown in Figs. 1 to 9, the up- 75 per sash is connected to the lower sash by 75 the pivot arms 7 which have direct pivotal connection with ears 8 secured to the upper sash. The other ends of said arms carry short pivot shafts 9 which have at their outer ends enlarged heads 10, and these 80 shafts 9 fit within split sleeves 11, carried by the bracket 12 mounted upon the upper edge of the lower sash. The sleeve 11 has at its inner end an interior flange 13, against which the enlarged head 10 of the shaft 9 85 abuts. The flange 13 has therein a slot 14 within which fits the rib 15 which is carried by the shaft 9, and which extends throughout a portion of the length of said shaft. It will 90 be observed that this arrangement of the lower pivot joint of the arm permits those arms to be moved laterally a certain distance which will be made sufficient to bring the two sashes out of line, as shown, and it will further be observed that the co-operating 95 action of the rib 15 and slot 14 prevents the arms turning on the pivot until the sashes have been moved out of line. In this form the upper sash is to be pulled out of line with the lower sash by manual operation 100 of the handles 16, and since a pull on these handles would tend to twist the upper sash on the upper pivotal connection I have provided means for connecting the bottom part of the upper sash with the casing of 105 the lower pivot during this lateral movement of the sash. This means embodies a hook 17 on the bottom of the upper sash, and an eye 18 on the bottom of the arm, and it will be observed that the turning of the link 110

arms 7 upon their pivots will at once disconnect this hook and eye. The other link arm 7 is provided with an eye 24 adapted to be engaged by a pin on the upper sash.

5 The split sleeve 11 is provided with a free end 19 which tends to separate from the other part of the sleeve by its resiliency, and which may be brought toward that other part by the thumb screw 20, thus clamping 10 the sleeve on the shaft 9 and its enlarged end 10. The split sleeve clamp thus enables me to firmly and securely fasten the upper sash in position over the lower sash, or to hold it in any desired position.

15 In the form shown in Fig. 1 the lower sash is provided with upwardly inclined portions or lugs 21 at its ends, and the upper sash has cutaway portions 22, fitting against these lugs, thus holding the upper sash more 20 surely in place.

By reason of the position of other parts of the motor vehicle it is necessary to lower the upper sash behind the lower sash, and where the upper sash is to be moved laterally in a 25 straight line until it is out of line with the lower sash the meeting edges of the sashes cannot be made inclined forward and downward, but are preferably made with an incline rearward and downward. This incline 30 nation however, while facilitating the rearward movement of the upper sash, will permit the passage of water, striking the front of the shield, down between the sashes, and to avoid this I have made the meeting edges 35 of the sashes in the form shown in Fig. 8. In this form the top of the lower sash is made in the shape of an inverted V, and the upper sash is made with a surface inclined rearward and downward, but has on its 40 front side a depending lip 23. Water striking the upper sash will pass downward and drop from the point of this lip, passing down the front side of the lower sash and will not pass back through the joint to the rear side 45 of the sash, and the V-shape of the lower sash will allow this lip to pass over that sash without contact therewith, and at the same time will permit the meeting edges of the two sashes to be at an incline rearward and 50 downward.

It will be observed that the arm 7 at one end of the sash is placed in line with the sash as shown at the left in Figs. 3 and 4, and that at the other end of the sash the arm 7 55 is placed immediately at one side of the sash. This is of course necessary, since in swinging upon the pivot arms the sash has some endwise motion and consequently both pivot arms could not be in line with it. As shown 60 in Fig. 5 when the upper sash is in lowered position, the hook 17 engages in an opening in the lower sash, thus holding sashes in proper position, and upon the other end of the sash there is a pin 24 which engages an 65 opening in plate 25 on the lower sash.

The parallel link arms 7 connected at opposite ends of the sashes will permit the upper sash to be moved endwise in the arc of a circle, and to be lowered vertically in a plane parallel with the lower sash, but it 70 will be apparent that during this lowering operation performed by hand there will be one point reached where one end of the upper sash may be made to move upward, while the other moves downward, and that thus 75 the connections may be broken or the sash left standing at an angle. To avoid this accidental disarrangement of the mechanism the two pivot arms may be connected so that they will necessarily move together, and that 80 there will be no dead center or point at which they may be turned in opposite directions. Any suitable means may be used connecting the two arms for this purpose, and in Fig. 9 I have shown a rod 26 pivotally 85 connected to ears 27 on the arms 7 so as to prevent this accidental twisting of the sash.

In the modified form shown in Figs. 10 to 13 I have disclosed an automatic means for moving the two sashes out of line at the 90 commencement of the swinging operation used in lowering the upper sash. It will be understood that most of the features described in connection with the other form of the invention shown are also applicable 95 to this modification, and that this modification is applicable to the form shown in the other figures. In this modified form a link arm 28 is pivotally connected to the lower sash at its top at 29, and this arm extends at 100 an inclination and is pivotally connected to a bracket 30 extending outwardly from the upper sash. At the other end of the sashes the link arm 31 is pivotally connected to the upper sash at 32 and is pivotally connected at its lower end to a bracket 33 extending outwardly from the top of the lower sash, thus making the arm 31 stand at an inclination parallel to the arm 28. This inclined arrangement of the link arms is used 110 so that the upper sash, when moved to the right in Fig. 10, will be automatically elevated above the lower sash during the first part of the swinging operation, and so that the meeting edges of the two sashes may be 115 made upon a plane extending forward and downward, as clearly shown in Fig. 12, without interfering with the rearward movement of the upper sash. In this form the rearward movement of the upper sash is secured by 120 the action of cam surfaces on the pivot sleeve 34, and upon the lower end of the link arm, as shown at 35. In this instance the link arm has sliding pivotal connection with the sleeve in substantially the same way as 125 shown in Figs. 3 to 6, except that there are no key connections between the parts. The cam surfaces may be of any desired form which will have the effect of moving the arms laterally as desired, and consequently 130

lengthwise of the pivot joint, and in Figs. 12 and 13 I have shown one form of cam for doing this. In this particular form the sleeve 34 has an inclined surface 36, against which bears a similar surface on the link arm, and it will be understood that there is another inclined surface like 36 and having the same inclination, thus forming practically a cam groove into which a portion of the link arm passes. The result is that when the link arms are turned in one direction the upper sash is automatically moved out of line with the lower sash, and when turned in the opposite direction the two sashes are automatically moved into a line. In the particular form shown, it is necessary by slight pressure on the part to bring the two cam surfaces into operation, but it is of course obvious that this might be done automatically. In this form of the invention I have provided bolts 37 on the ends of the upper sash adapted to lock the sash in position, thus preventing accidental turning of the sash upon the link arms.

25 It will be understood that when the upper sash is moved rearwardly an opening is formed between the sashes permitting the passage of a current of air. The upper sash may be held in this position by the 30 clamping action of the split sleeves 11.

Having thus described the invention, what is claimed is:—

1. A wind shield comprising a lower sash, an upper sash, parallel links connecting said 35 sashes for guiding the upper sash by an endwise movement to a position against the lower sash, and sliding connection between said links and one of said sashes permitting the sash to be moved at right angles to the 40 plane of the sash.

2. A wind shield comprising a lower sash, an upper sash, means connecting said sashes permitting a lateral movement of the upper sash in the plane of said sash, and means for 45 guiding the upper sash by an endwise movement in a plane parallel to the plane of the lower sash to a position against the lower sash.

3. A wind shield comprising a lower sash 50 and an upper sash, the upper sash being arranged normally in a plane with the lower sash and connected to move bodily rearward a slightly greater distance than its thickness, and means for swinging the upper sash 55 in its own plane to a position in the rear of and against the lower sash.

4. A wind shield comprising a lower sash and an upper sash, and means connecting said sashes and permitting the upper sash to 60 be moved bodily out of line with the lower sash and for swinging the upper sash in its own plane to a position alongside of the lower sash.

5. A wind shield comprising a lower sash 65 and an upper sash, the upper sash being ar-

ranged normally in a plane with the lower sash, and link connections between said sashes permitting the upper sash to be moved bodily out of line with the lower sash, and for swinging the upper sash in an 70 edgewise movement to a position alongside of the lower sash.

6. A wind shield comprising a lower sash and an upper sash, the upper sash being arranged normally in a plane with the lower 75 sash, parallel link arms pivotally connected to said sashes and adapted to swing in a plane parallel to one of the sashes, and means permitting the movement of the upper sash out of line with the lower sash. 80

7. A wind shield comprising a lower sash and an upper sash, the upper sash being arranged normally in a plane with the lower sash, parallel link arms pivotally connected to said sashes and adapted to swing in a 85 plane parallel to one of the sashes, and sliding connections for the pivots on one of said sashes permitting the movement of the upper sash out of line with the lower sash.

8. A wind shield comprising a lower sash 90 and an upper sash, the upper sash being arranged normally in a plane with the lower sash, parallel link arms pivotally connected to the upper sash above the bottom and having sliding pivotal connection with the bottom sash at the top, the said pivotal connections being arranged transversely of the sashes, whereby the two sashes may be moved out of line. 95

9. A wind shield comprising a lower sash 100 and an upper sash, the upper sash being arranged normally in a plane with the lower sash, parallel link arms pivotally connected to the upper sash and having a sliding pivotal connection with the lower sash, the said 105 pivotal connections being arranged transversely of the sashes and the link arms being movable in a plane parallel to the sashes whereby one of the sashes may be moved out of alignment with the other sash, and means 110 for clamping the upper sash in the non-aligned position.

10. A wind shield comprising a lower sash and an upper sash, the upper sash being arranged normally in a plane with the 115 lower sash, parallel link arms pivotally connected to the upper sash and having a sliding pivotal connection with the lower sash, the said pivotal connection being arranged transversely of the sashes, and the link arms 120 being movable in a plane parallel to the sashes whereby one of the sashes may be moved out of alignment with the other sash, and means including a clamp for securing 125 the upper sash in both the aligned and non-aligned positions.

11. A wind shield comprising a lower sash and an upper sash, the upper sash being arranged normally in a plane with the lower sash, parallel link arms pivotally con- 130

- 5 nected to the upper sash above the bottom thereof and having sliding pivotal connection with the lower sash at the top thereof, the said pivotal connections being arranged transversely of the sashes, and the link arm being movable in a plane parallel to the sashes whereby one of the sashes may be moved out of alinement with the other sash, and positive connections preventing lateral separation between the bottom of the upper sash and the link arms when the arms are in upright position.
- 10 12. A wind shield comprising a lower sash and an upper sash, the upper sash being arranged normally in a plane with the lower sash, parallel link arms pivotally connected to the upper sash above the bottom arranged to turn in a plane parallel to said sash and having sliding pivotal connection with the bottom sash at the top, whereby the two sashes may be moved out of line, the bottom of the top sash and the link arms being provided with lugs and corresponding eyes interengaging to prevent separation of the arms and sash until the sashes are out of line.
- 15 13. A wind shield comprising a lower sash and an upper sash, the upper sash being arranged normally in a plane with the lower sash, parallel link arms pivotally connected to the upper sash above the bottom and having sliding pivotal connection with the bottom sash at the top the pivots being at right angles to the plane of the sash whereby the two sashes may be moved out of line, positive connection preventing lateral separation between the bottom of the top sash and the link arms when the arms are upright, and handles on the lower part of the upper sash.
- 20 14. A wind shield comprising a lower sash, an upper sash, parallel links having independent pivotal connections with the sashes and arranged to swing in a plane parallel to one of the sashes to permit the upper sash to swing to and from a position alongside of the lower sash, and a stop adapted to limit the upward swinging of the upper sash.
- 25 15. A wind shield comprising a lower sash and an upper sash, the upper sash being arranged normally in a plane with the lower sash, means connecting said sashes permitting the upper sash to be moved bodily out of alinement with the lower sash, means for swinging the upper sash in a parallel plane against the lower sash, and means, including a clamp, for securing the upper sash in position above the lower sash.
- 30 16. A wind shield comprising a lower sash and an upper sash, the upper sash being arranged normally in a plane with the lower sash, parallel link arms connected to said sashes by pivots at right angles to the plane of the sash permitting the sashes to

have relative swinging motion in parallel planes, means permitting the movement of the upper sash out of line with the lower sash, and means for clamping the upper sash in position.

70

17. A wind shield comprising a lower sash and an upper sash, the upper sash being arranged normally in a plane with the lower sash, parallel link arms connected to said sashes by pivots arranged normally to the plane of the sashes and permitting the sashes to have relative swinging motion in parallel planes, sliding connections for the pivots on one of said sashes permitting the movement of the upper sash out of line with the lower sash, and means for clamping said connection to prevent sliding.

80

18. A wind shield comprising a lower sash and an upper sash, the upper sash being arranged normally in a plane with the lower sash, parallel link arms pivotally connected to the upper sash above the bottom and having sliding pivotal connection with the bottom sash at the top whereby the two sashes may be moved out of line, and split sleeve clamps constituting the sliding pivots.

90

19. A wind shield comprising a lower sash and an upper sash, the upper sash being arranged normally in a plane with the lower sash, parallel link arms pivotally connected to the upper sash above the bottom thereof and having sliding pivotal connection with the lower sash at the top thereof, whereby one of the sashes may be moved out of alinement with the other, and split sleeve clamps constituting the bearings for said pivots, the said pivots being provided with keys adapted to prevent the lowering of the upper sash below the upper edge of the lower sash until the sashes are out of alinement.

95

20. A wind shield comprising a lower sash, an upper sash, parallel links having independent pivotal connections with said sashes and adapted to be swung in a plane parallel to one of the sashes to permit the upper sash to be folded against the lower sash by an edgewise swinging movement of the former.

100

21. A wind shield comprising a lower sash, an upper sash, a pair of links having independent pivotal connections with said sashes, the connections with one sash being out of alinement with the connections with the other sash in a direction transverse of the plane of one of the sashes, and means connecting said links adapted to hold them in parallelism.

115

22. A wind shield comprising a lower sash, an upper sash, parallel pivoted links connecting said sashes, and a connecting rod having an eccentric connection with one of the pivots of each of the links to cause the links to move together.

125

23. A wind shield comprising a lower

130

sash, and an upper sash adapted to be moved forward into line with the lower sash and to rest thereon, the meeting edges of said sashes being cut at an angle to permit easy 5 rearward movement of the upper sash without lifting the upper sash from the lower sash, the forward portion of the upper edge of the lower sash being cut away so as to incline forward and downward, and the 10 forward portion of the lower edge of the upper sash being provided with a depending lip the lower edge of which is above the highest point of the upper edge of the lower sash.

15 24. A wind shield comprising a lower

sash and an upper sash, the upper sash being arranged normally in a plane with the lower sash, means connecting said sashes whereby the upper sash is adapted to be moved bodily out of alignment with the 20 lower sash, and said connecting means being adapted to guide the upper sash in an edgewise motion of pure translation in a circular path.

In testimony whereof I affix my signature 25
in presence of two witnesses.
